HORIZONTAL CORE MACHINE

Henry G. Floyd, Birmingham, Ala., assignor to
McWane Cast Iron Pipe Co., Birmingham,
Ala.

Original application October 27, 1936, Serial No.
107,889. Divided and this application April 20,
1938, Serial No. 203,173

5 Claims. (Cl. 22—12)

The invention relates to new and useful improvements in horizontal core machines for making green sand cores employed in the manufacture of cast iron pipes or similar hollow cylindrical castings. This application is a division of my copending application for Letters Patent filed October 27, 1936, Serial No. 107,889, for improvements in Horizontal core machines.

Among the several objects of this invention are to provide means for supporting a core bar for horizontal rotation about its longitudinal axis to receive a thin sheet of green sand from a suitable sand feeding means located thereabove; to provide means for continuously rotating the core bar at a constant speed and for retaining the same against endwise movement; to provide a pattern knife for shaping the core being made; to provide means for adjustably setting the knife with respect to the core; to provide a knife of removable sections; to provide a holder for the knife which together with the knife constitutes a readily removable unit; to provide manually operable means for moving the knife from an operative position to an inoperative position whereby the finished core may be removed without contacting the knife, and to provide a deflector associated with the knife for directing surplus sand to the bottom hopper.

With these and other objects in view which will more fully appear, the nature of the invention will be more clearly understood by following the description, the appended claims, and the several views illustrated in the accompanying drawings.

35 In the drawings:

Figure 1 is an end elevation illustrating the invention,

Figure 2 is an enlarged rear elevation of the core bar support and pattern knife mounting,

40 Figure 3 is a left end elevation thereof,

Figure 4 is a right end elevation thereof,

Figure 5 is an enlarged sectional view taken on the line 5—5 of Figure 4,

45 Figure 6 is an enlarged sectional view taken on the line 6—6 of Figure 4,

Figure 7 is an enlarged sectional view taken on the line 7—7 of Figure 3,

Figure 8 is an enlarged front elevation of the 50 construction shown in Figure 2,

Figure 9 is a top plan view thereof, the knife supporting channel bar being shown in section,

55 Figure 10 is an enlarged cross section taken on the line 10—10 of Figure 3 and showing the pattern knife in operative position,

Figure 11 is a similar view but showing the knife in its inoperative position,

Figure 12 is a detail section showing the stops for the crank shaft,

Figure 13 is a vertical section taken on the line 13—13 of Figure 2,

Figure 14 is a perspective view of the pattern knife,

Figure 15 is a perspective view of the knife holder,

Figure 16 is a perspective view of the knife support,

Figure 17 is a perspective view of the deflector plate,

Figure 18 is a perspective view of one of the hangers,

Figure 19 is a perspective view of one of the eye bolts, and

Figure 20 is a perspective view of another eye bolt.

Like reference numerals designate corresponding parts throughout the several figures of the drawings.

25 The core bar

The core bar J includes an elongated tubular body portion 103 of metal having an enlarged end portion 104 which is provided with an annular flange 105. See Figures 2, 4 and 8.

30 The core bar support

The core bar J is mounted on a support I for horizontal rotation about its axis directly below a sand feeding means generally designated F. The support I includes a pair of spaced standards 106, 107 which are mounted on the floor or ground.

35 Mounted on the standard 106 is a post 108 which is formed by a metal plate, and rotatably mounted on the upper end thereof are two idler 40 rollers 109, 110 of like diameters, and having their axes in a common horizontal plane. These rollers are spaced a short distance apart and conjointly form a rolling support for the body portion 103 of the core bar. Preferably these 45 rollers are provided with tires 111, 112 of rubber or other suitable material for frictionally contacting the core bar.

45 Mounted on the standard 107 is a post 113 which is hollow to form a gear casing. Journaled in the upper portion of the post 113 are two horizontal driven shafts 114, 115 whose axes are in a common horizontal plane. Fixed on the inner ends of these shafts are driven rollers 116, 117 which are of like diameters and are spaced 55

apart and conjointly form a rolling support for the enlarged end portion 104 of the core bar. These rollers are preferably provided with tires 118, 119 of rubber or other suitable material for frictionally contacting the core bar. Fixed on the shafts and located within the hollow posts 113 are driven gears 120, 120 of like diameters. The gears 120, 120 are rotated in the same directions by a driving gear 121 which is also located 5 within the hollow post 113. This gear 121 is fixed to a drive shaft 122 journaled in the post 113 below the driven shafts 114, 115. The outer end of the drive shaft is provided with a pulley 123 which is driven by a belt 124 from an electric motor 125. See Figure 1. It will therefore be seen that the core bar J is continuously rotated at a constant speed. Access to the gears 10 may be had by removing a cover plate 126 which closes an opening in the rear side of the hollow 15 post 113. See Figure 13.

Fixed on the outer end of the driven shaft 114 is a grooved roller 127 which receives the flange 105 of the core bar and thereby retains the latter against endwise movement although permitting 20 rotation thereof. Thus, that portion of the core bar which receives the coating of sand from the sand feeding means F, is maintained in register with said means and with the pattern knife hereinafter described.

30   *The pattern knife and support therefor*

Secured to the posts 103, 113 of the support are inwardly extending brackets 128, 129, and disposed intermediate said brackets is a supporting bar 130 preferably of channel shape and including a vertical web 131 and top and bottom flanges 132, 133. This supporting bar is disposed in parallelism with the core bar J and is located below and slightly in rear thereof. 35 This supporting bar 130 is rigidly connected to the bracket 128, 129 through the medium of coupling plates 134, 135 which overlap the brackets and the adjacent ends of the bar. The inner ends of the plates are welded or otherwise rigidly secured to the web 131 of the bar and the outer ends of the plates are rigidly and removably secured to the brackets by screws 136 and 137.

40   Rigidly secured to the top flange 132, preferably by welding, are spaced brackets 138, 138 of similar construction. Each bracket includes a pair of spaced forwardly extending arms 139, 139 which overhang the front face of the bar 130, the rear face 140 of the bracket being upwardly and forwardly inclined. See Figures 10, 11 and 16.

45   A holder 141 for the pattern knife K is of angle iron construction and includes an upwardly inclined flange 142 and a downwardly inclined flange 143. Secured to the rear face of the downwardly inclined flange 143, preferably by welding, are spaced transverse supporting arms 144, 144 of similar construction. Each supporting arm is formed at its upper end with a rearwardly and downwardly extending hook 145, the lower end of the arm projecting below the flange 143 and 50 formed into a forwardly and upwardly extending hook 146. The hooks 145 are removably pivoted on horizontal pins 147, 147 mounted in the overhanging arms 139, 139. See Figures 10, 11, 15 and 16. The pattern knife K is removably attached to the upper face of the flange 142 of the holder by screws 148 which project through transverse slots 149 in the knife whereby the knife 55 may be adjusted forwardly or rearwardly on the holder. Preferably the knife is formed of a plurality of interchangeable sections 150. See Figure 13.

ures 2 and 14. Thus it will be seen that the knife K is supported for swinging movements about an axis disposed in parallelism with the core bar, whereby the knife may be moved from an operative position to an inoperative position, and vice versa. It will also be observed that the knife K together with the holder 141 may be readily removed as a unit from the support 130 whenever it is desired to substitute another knife. The ends of each pivot pin 147 project beyond the arms 10 130, and pivotally supported thereon is a lever 151. Each lever is formed of metal and includes spaced vertical arms 152, 152 which are connected by upper and lower webs 153, 154 and an intermediate web 155. The upper web 153 extends 15 forwardly of the arms 152 to form a downwardly inclined arm 156. The lower web 154 extends forwardly of the arms 152 beyond the forward end of the arm 156 to form a guide arm 157 having a guide opening 158 therein which is located directly below the associated hook 146. It will be 20 observed that these levers 151 are located in front of the supporting bar 130. The intermediate web 155 extends rearwardly beyond the arms 152 to form a cam follower 159. An adjustable stop screw 160 which is threaded into an opening 161 located in each supporting arm 144 between the flange 143 and the hook 146, bears against the downwardly inclined arm 156 of the lever 151 for the purpose of providing means for adjusting the 25 position of the knife edge with respect to the coating of sand on the core bar. This permits the knife to be accurately set for a core of a predetermined diameter. Yieldable means are provided for retaining each stop screw 160 in contact with the arm 156. To this end, the eye 162 of an eye-bolt 163 is engaged in the hook 146 of the associated supporting arm 144, and the lower end of the bolt is projected through the guide opening 158 of the guide arm 157. A nut 164 is 30 threaded onto the lower end of the bolt and a coil spring 165 is interposed between the guide arm 157 and the nut 164. By means of the nut 164 the yielding contact between the stop screw 160 and the arm 156 may be adjusted to suit conditions. See Figures 10 and 11.

45   It is desirable to provide manually operable means for moving the knife K from its operative position to an inoperative position immediately following the completion of each core in order to allow the core to be withdrawn without contacting the knife. For this purpose, a cam shaft 166 is supported longitudinally of the supporting bar 130 in spaced bearings 167, 167 secured to the rear face of the web 131. Cams 168, 168 50 are fixed to the cam shaft and in register with the cam followers 159, 159 which project rearwardly through openings 169, 169 formed in the web 131. Each cam follower 159 is held in yieldable contact with the associated cam 168. An eye bolt 170 projects through an opening 171 in the web 131, and the eye 172 thereof has pivotal connection with a pivot pin 173 which is positioned in the lever 151 between the lower web 154 and the intermediate web 155, the ends of the pin 55 being mounted in the walls 152 of the lever. A nut 174 is threaded onto the rear end of the bolt and a coil spring 175 is interposed between the nut and the web 131. A crank handle 176 is journaled in the post 108 and is connected to the cam shaft 166 by means of a coupling 177. The cam shaft is provided with a radially projecting stop arm 178 for engagement with either one of upper and lower stops 179, 180 welded to the rear face 60 of the web 131 and respectively located above and 65 below the lever 151. The cam shaft 166 is journaled in the post 108 and is connected to the cam 70 shaft 166 by means of a coupling 177. The cam shaft is provided with a radially projecting stop arm 178 for engagement with either one of upper and lower stops 179, 180 welded to the rear face 75 of the web 131 and respectively located above and 75

below the cam shaft. See Figures 2 and 12. Thus when the knife K is in its operative position, the stop arm 178 is bearing against the lower stop 180 as shown in Figure 12, and the low parts of 5 the cams 168 are contacting the cam followers 159. Consequently when the crank handle 176 is rotated 180 degrees, the stop arm 178 will contact the upper stop 179 and the cams 168 will swing the levers 151 forwardly, which through 10 the medium of the adjusting screws 160 will swing the knife K rearwardly away from the finished core. When the crank shaft 178 is rotated in the opposite direction, the cams 168 will be rotated, the levers 151 will be returned to their initial 15 positions by the springs 175, the knife holder 141 together with the knife K being returned to their initial or operative position by the springs 165, and the stop arm 178 will contact the lower stop 180.

20 A downwardly and rearwardly inclined deflector plate 181 extends longitudinally above the cam shaft 166 with the upper edge thereof underlying the lower edge of the knife K. This plate is attached by screws 182 to the inclined faces 140 of 25 the brackets 138. An intermediate supporting bracket 183 is welded to the upper flange 132 of the supporting bar 130, and the central portion of the deflector plate is attached thereto by a screw 184. The surplus sand from the core which 30 is being formed, gravitates onto the knife K and from the knife the sand is directed by the deflector 181 over the cam shaft 166 and into the bottom sand hopper B. See Figure 1.

In operation, a core bar J is positioned on the 35 rollers of the support I, and the bar is continuously rotated at a constant speed through suitable power transmitting connections 124 from the motor 125. A thin sheet of sand gravitates onto the core bar throughout the length thereof 40 corresponding to the length of the core to be made. As the sand builds up on the core bar, the core thus being formed is shaped by the pattern knife K, and the surplus sand from the core is directed into the bottom hopper B by the deflector plate 181. As soon as the core has been 45 formed, feeding of sand from the means F is discontinued and the pattern knife K is swung to its inoperative position by the crank handle 176, and the core can then be removed without contacting the knife K.

50 It is of course to be understood that the details of structure and arrangement of parts may be variously changed and modified without departing from the spirit and scope of my invention.

55 I claim:

1. In a horizontal core machine, the combination with means for supporting a core bar for horizontal rotation about its longitudinal axis, 60 of a pattern knife associated with the core bar

for shaping the core, and manually operable means including a cam shaft and a lever operated thereby for moving the knife from an operative to an inoperative position.

2. In a horizontal core machine, the combination with means for supporting a core bar for horizontal rotation about its longitudinal axis, of a pattern knife mounted on the holder for shaping the core, a lever pivoted on the support, means for yieldably retaining the holder in contact with the lever, a manually operable cam shaft mounted on the support, a cam on said shaft, a cam follower mounted on the lever, and means connecting the lever and the support for yieldably retaining the cam follower in contact with the cam. 5

3. In a horizontal core machine, the combination with means for supporting a core bar for horizontal rotation about its longitudinal axis, of a pattern knife associated with the core bar for shaping the core, manually operable means 10 including a cam shaft mounted on the support for moving the knife from an operative position to an inoperative position, and a deflector plate mounted on the support above the cam shaft and underlying the knife for directing surplus sand 15 from the knife over the cam shaft. 20

4. In a horizontal core machine, the combination of a pattern knife, drive rollers for supporting and imparting rotation to a core bar in position for having a sand core building up thereon 25 engaged by said knife, spring means for urging the knife into contact with said building sand core, manually operable rotary cam means for moving the knife out of contact with said sand core against the action of said spring means, and stop means for limiting rotary movement of the cam means in each direction for determining limits of movement of the knife toward and from the sand core. 35

5. In a horizontal core machine, the combination of a pattern knife, drive rollers for supporting and imparting rotation to a core bar in position for having a sand core building up thereon 40 engaged by said knife, spring means for urging the knife into contact with said building sand core, manually operable rotary cam means for moving the knife out of contact with said sand core against the action of said spring means, stop means for limiting rotary movement of the cam means in each direction for determining limits of movement of the knife toward and from the sand core, and additional adjustable means for varying the knife positioning effect of said rotary movement limiting stop means. 45

HENRY G. FLOYD. 50
